UNITED STATES PATENT OFFICE.

HENRY F. KALVELAGE, OF PORTLAND, OREGON.

TURBINE.

1,101,077.

Specification of Letters Patent. Patented June 23, 1914.

Application filed July 15, 1912. Serial No. 709,499.

To all whom it may concern:

Be it known that I, HENRY F. KALVELAGE, a citizen of the United States, residing at Portland, in the county of Multnomah and 5 State of Oregon, have invented certain new and useful Improvements in Turbine-Engines, of which the following is a specification.

My present invention has to do with fluid 10 pressure engines of the turbine type; and it has for its object to provide such an engine possessed of high efficiency.

To the attainment of the foregoing object, the invention consists in the peculiar 15 and advantageous disks and the relative arrangement of the same in a casing as hereinafter described and definitely claimed.

In the accompanying drawings which are hereby made a part hereof, Figure 1 is an 20 elevation of three compounded engines arranged to drive a common shaft. Fig. 2 is a section taken in the plane indicated by the line 1—1 of Fig. 1, looking toward the left. Fig. 3 is an enlarged diametrical 25 section showing a turbine engine constructed in accordance with my invention and also illustrating the provision for the exhaust of steam or other expansive fluid adjacent the center of movement of the disks. Fig. 30 4 is a section taken at a right angle to Fig. 3 and showing the means for conducting expansive agent into the chamber. Fig. 5 is a detail view, partly in section and partly in elevation, showing the spaced disks 35 fixed to the shaft. Fig. 6 is a detail section showing portions of a group of disks on the shaft and also showing the manner in which the disks diverge toward their center of movement. Fig. 7 is a perspective 40 view of one of the peculiar and advantageous disks.

Similar letters of reference indicate corresponding parts in all of the views of the drawings.

45 In furtherance of my invention one or a plurality of casings *h* are suitably supported about a shaft *c*, journaled in boxings or standards *n* or other approved supporting means. The said casings *h* are identical in 50 construction and therefore, a detailed description of the one shown in Figs. 3 and 4 will suffice to impart a definite understanding of all. The specific casing referred to is provided with central lateral projections 55 from which lead exhaust conduits *k* and *m*. The said casing is also connected to con-

duits *i* and *j* adapted to be connected with a source of steam or other fluid pressure supply, the conduits *i* being employed when the shaft *c* is to be rotated in one direction, 60 and the conduits *j* when the shaft is to be rotated in the opposite direction.

Disposed in the casings *h* and fixed by means of a pin *e* and a key *f* on the shaft *c* and between collars *g*, Fig. 3, are disks *a* 65 which constitute the rotor of the engine. The said disks *a* are concavo-convex and are retained in spaced relation on the shaft *c* by collars *d*. It will also be manifest by reference to Fig. 3 that the groups of disks *a* at opposite sides of the vertical center of 70 the engine are reversely arranged so that the concave sides of all the disks will be toward said center. It will also be manifest by comparison of Figs. 3 and 6 that I prefer to separate the two groups of reversely 75 arranged disks *a* by a vertical central and convexo-convex disk, and by reference to Figs. 4 and 7 it will be seen that each concavo-convex disk *a* is provided with three 80 (more or less) apertures *b* for the passage of steam or other expansive agent to the exhaust conduits *k* and *m*. The steam inlet conduits are arranged tangentially to the disks *a*, and by virtue of this and the disposition of the exhaust apertures or ports *b* adjacent the center of the disks, the full area 85 of the disk surfaces are utilized to advantage.

The merit of my novel turbine will be 90 better appreciated when it is stated that in turbines extant the expansive agent is directed against movable vanes or buckets and more or less of an eddy is formed at the rear of the buckets and the said turbines 95 cannot be reversed. Moreover in some turbines a smooth flat disk has been employed in combination with a drum and a central shaft. This type is objectionable since only 100 a small portion of the disk surfaces is in actual contact with the expansive agent employed. Again some turbines include smooth flat disks so arranged as to exhaust at or adjacent their center of movement. This type depends altogether upon the viscosity 105 of the fluid under pressure intensified to a greater or less extent by the velocity with which the fluid under pressure strikes or is directed against the disks. These turbines are open to objection because they cannot 110 attain maximum efficiency owing to the fact that the viscosity of the fluid under pres-

sure only is utilized, and no resistance is offered to the free passage of the fluid under pressure between the disks. In my invention the disks *a* diverge from their peripheries to their center of movement, and my said invention overcomes all of the difficulties or objections mentioned. It will also be manifest that my novel turbine is calculated to utilize the maximum power of the expansive agent employed during the varying stages of expansion in the first unit without compounding.

The concavo-convex disks comprised in my engine diverge toward the center of movement as stated. Hence the said disks utilize in addition to the viscosity of the expansive agent the expansion thereof by providing the proper relative clearance. Thus the increased volume of available space toward the center of the disks is proportionate to the increasing volume of expansive agent, and in addition the concavo-convex surfaces of the disks utilize to advantage the viscosity of the expansive agent. The concavo-convex disks are highly efficient since they are calculated to laterally deflect the course of the agent employed, and allow such agent to exhaust at an obtuse angle instead of at a right angle as is the case of turbines extant. This obviates the objectionable back pressure, and the peculiar outline of the concavo-convex disks also affords a large working surface and resistance, and intensifies the viscosity of the expansive agent employed.

The arrangement of the reversely arranged disks at opposite sides of the vertical center of the engine renders the rotor balanced at all times since the pressure on one side thereof will be counteracted by the pressure on the other side, the tangential disposition of the supply conduits obviating side pressure incidental to the admission of the expansive agent. Moreover it will be manifest that my novel turbine will develop as much power running backward as when running forward; also the turbine can be compounded to the extent desired.

It will, of course, be understood that by an obvious reversal in the arrangement of the fluid inlets and outlets the device may be used as a pump for water, air or any other fluid volatile substance.

Having described my invention, what I claim and desire to secure by Letters Patent, is:

1. The combination in a turbine engine, of a shaft, a casing surrounding the same and having inlet and exhaust ports for fluid under pressure, and concavo-convex disks fixed on the shaft and disposed in the casing.

2. The combination in a turbine engine, of a shaft, a casing surrounding the shaft and having inlet and exhaust ports for fluid under pressure, and reversely arranged sets of

concavo-convex disks fixed on the shaft and disposed in the casing and having their convex sides outermost.

3. In a turbine engine, the combination of a shaft, a casing surrounding the same and having exhaust ports adjacent its center and longitudinally disposed inlet ports in its peripheral portion, a vertical central disk fixed on the shaft and disposed in the casing, and sets of reversely arranged concavo-convex disks fixed on the shaft and disposed in the casing at opposite sides of the first named disk and having ports adjacent their center of movement.

4. In an elastic fluid turbine, a rotor disk having a concaved face to receive the impelling force of the fluid.

5. In an elastic fluid turbine, a rotor including a plurality of concavo-convex disks arranged side by side and having their concaved sides facing in a common direction.

6. In an elastic fluid turbine, a rotor including a plurality of concavo-convex disks arranged side by side and having their concaved sides facing in a common direction, said disks being arranged to diverge between their peripheries and centers.

7. In an elastic fluid turbine, a rotor including two sets of concavo-convex disks, the disks of each set having their concaved sides facing in the same direction, and the disks of the two sets having their concaved sides facing in opposite directions.

8. In an elastic fluid turbine, a rotor comprising two sets of concavo-convex disks, and an intermediate disk, the concaved sides of one set of disks facing in one direction and the concaved sides of the other set of disks facing in the opposite direction.

9. In an elastic fluid turbine, a shaft, a plurality of concavo-convex disks fixed to the shaft, said disks having their concaved sides facing in a common direction, a casing inclosing said disks, means for supplying an elastic motive fluid at or adjacent to the peripheries of said disk, and means for exhausting said fluid at or near the centers of motion of said disks.

10. In an elastic fluid turbine, a shaft, a plurality of concavo-convex disks fixed to the shaft and having their concaved sides facing in a common direction, a casing surrounding the disks, said disks being provided at or near their centers with exhaust ports, means for admitting fluid pressure to the casing at or near the peripheries of said disks, and means for exhausting the spent fluid from the casing.

11. In an elastic fluid turbine, a shaft, a plurality of sets of concavo-convex disks fixed to the shaft, an intermediate disk separating said sets of concavo-convex disks from each other, the said concavo-convex disks being provided with exhaust ports at or near their centers, a casing surrounding

the shaft and sets of disks and having lateral exhaust ports at opposite sides thereof, and means for admitting fluid pressure to the casing at or adjacent to the peripheries 5 of the sets of disks.

12. In an elastic fluid turbine, a rotor disk to receive the impelling force of the fluid, said disk being of concavo-convex form.

13. In an elastic fluid turbine, a rotor disk 10 having a concaved face to receive the impelling force of the fluid, means for supplying the fluid for impingement against said concaved face at or adjacent to the periphery of said disk, and means for exhausting 15 the fluid at or near the center of motion of said disk.

14. In an elastic fluid turbine, a rotor including a plurality of spaced disks arranged side by side and diverging from their peripheries toward their center of motion, 20 means for supplying an expansive fluid

agent at or near the peripheries of said disks, and means for exhausting the spent fluid at or near the center of motion of the disks.

15. In an elastic fluid turbine, a rotor including a plurality of concavo-convex disks, disposed side by side, said disks having their concaved sides facing in a common direction, and being arranged to diverge between 30 their peripheries and centers, means for supplying an expansive fluid agent at or near the peripheries of said disks, and means for exhausting the spent fluid at or adjacent to the centers of the disks.

35 In testimony whereof I affix my signature in presence of two witnesses.
